CLAIM

We claim the ornamental design for a vapocoolant device, as shown and described.

DESCRIPTION

FIG. 1 is a perspective view of a vapocoolant device showing our new design;

FIG. 2 is a front view of the vapocoolant device;

FIG. 3 is a back view of the vapocoolant device;

FIG. 4 is a side view of the vapocoolant device;

FIG. 5 is an opposite side view of the vapocoolant device;

FIG. 6 is a top view of the vapocoolant device;

FIG. 7 is a bottom view of the vapocoolant device;

FIG. 8 is a perspective view of a vapocoolant device showing our new design;

FIG. 9 is a front view of the vapocoolant device;

FIG. 10 is a back view of the vapocoolant device, the side views being symmetric;

FIG. 11 is a top view of the vapocoolant device; and,

FIG. 12 is a bottom view of the vapocoolant device.

The broken lines or dotted sections in any of the foregoing figures are directed to environment and are for illustrative purposes only; the broken lines form no part of the claimed design. The dash-dash lines illustrate portions of the vapocoolant device that form no part of the claimed design. The dash-dash-dot broken lines illustrate a label that form no part of the claimed design. The additional dash-dash-dot broken lines shown on the top surface in FIGS. 1, 4-8, 11 and 12 illustrates a tab that forms no part of the claimed design.
